FREQUENCY MODULATED OSCILLATOR
CONTROLRichard H. Ranger, United States Army,
Newark, N. J.

Application October 2, 1944, Serial No. 556,815

17 Claims. (Cl. 250—36)

(Granted under the act of March 3, 1883, as
amended April 30, 1928; 370 O. G. 757)

1

The invention described herein may be manufactured and used by or for the Government for governmental purposes, without the payment of any royalty thereon.

This invention relates to means for keeping the output frequency of an electric oscillator substantially constant.

An object of this invention is to provide a frequency control in which a frequency-modulated oscillator is employed as a reference or basis.

More specifically, it is an additional object of my invention to afford a frequency controller comprising a crystal-controlled oscillator which provides frequencies of great stability, a controlled oscillator containing an adjustable part by movement of which its output frequency is varied, a frequency-modulated oscillator having a limited range of output frequencies, a source of frequencies providing said frequency-modulation, a first mixer-detector in which the output frequencies of said crystal-controlled oscillator and of said controlled oscillator are combined, a second mixer-detector in which the output from said first mixer-detector and the output from said frequency-modulated oscillator are combined in such phase relationship that the output frequency of said second mixer-detector is in phase with the frequency output of said source when the output of the first mixer-detector is of higher frequency than that of the frequency-modulated oscillator, and that the output frequency of said second mixer-detector is 180° out of phase with the frequency output of said source when the output of the first mixer-detector is of lower frequency than that of the frequency-modulated oscillator, a split-phase motor having coils energized respectively by the output of said source and by the output of said second mixer-detector, and a mechanical connection between said motor and said adjustable part whereby said motor moves said adjustable part to bring the output frequency of said controlled oscillator to the desired value.

Furthermore, coupling means are provided working from the output of the second mixer-detector so that at higher values of frequency of said output, this output will be increased. In conjunction with the coupling means, automatic volume control means are utilized for the purpose of increasing the output of the second mixer-detector when the volume of that component of such output which has a frequency corresponding to that of the source of frequencies providing frequency-modulation, is comparatively low. The same automatic volume control means are so arranged as to decrease the frequency swing of the

2

frequency-modulated oscillator circuit as the frequency of the controlled oscillator approaches its desired value.

I have described and illustrated a preferred embodiment of my invention in the annexed specification and drawing to which reference is now made.

The single figure of the drawing is a block diagram.

10 We start with a crystal 1 as seen in the drawing. Let it be assumed that this is a 200 kc. crystal. The harmonic amplifier 2 will then build up the output of this crystal to give rich harmonic content. Harmonic selector 3 will pick out the particular harmonic desired for reference. The controlled oscillator 14 at the bottom will pass some of its energy up into the first mixer-detector 5 along with the output frequency of the harmonic selector 3 and give a first beat, constant in frequency.

15 The output of the first mixer-detector 5 is combined with that of an adjustable oscillator 6 covering a band of frequencies from 200 to 400 kc. If the frequency of the controlled oscillator 14 is 200 kc. away from the selected harmonic in 3, we will have a 200 kc. beat coming out of the first mixer-detector.

20 If this is combined with a 200 kc. setting of the oscillator 6, we would get 0 beat in the second mixer-detector 1. However, this, of course, would only be by chance. Let it be assumed that the first mixer-detector 5 is putting out a frequency of 210 kc. We will then have a difference frequency at second mixer-detector 1 of 10 kcs. between the 25 200 kc. setting of oscillator 6 and the output of the first mixer-detector 5.

25 Now assume that we have a 60-cycle source shown at 18. This 60 cycle works through a gain control 16 to give a mechanical vibration to the 30 plates of the trimmer condenser 20 connected to oscillator 6. As is well known, the gain control 16 may be caused to impart this mechanical vibration to the plates of condenser 20 by feeding output of gain control 16 to an electromechanical 35 translating device 21 which may be of a conventional type as an electrodynamic or magnetic loudspeaker having its armature connected either directly or through some form of mechanical coupling to the condenser plates. Common solenoids may also be used as the translating devices. The net result will be to give a frequency modulation to the output of this oscillator 6 at the rate of 60 cycles. Let it be assumed that the phases are such that for a rising 60 cycle pulse, the frequency of the oscillator 6 is raised. We will then

have an output going over to the second mixer-detector 7 which will give with the 210 kc. coming from the first mixer-detector 5 a second wobbled beat as the output of 7. As the frequency put out by the local oscillator 6 rises, it will approach that of the beat coming out of mixer-detector 5 so that we will get a reduction in frequency in the output of the second mixer-detector 7 on positive swing. In other words, the frequency will decrease on positive swing when the local oscillator frequency is below that of the beat frequency coming from 5. On the contrary, if the output of the first mixer-detector 5 was below 200 kc., say 190 kcs., the frequency of the output of mixer-detector 7 would rise on positive swings given the local oscillator 6. So we have here a complete reversal in action, depending upon whether the first mixer-detector output is below or above that of the local oscillator 6. Capacity coupling 8 is introduced in the output of second mixer-detector 7 such that for higher frequencies, more output will be obtained. Under these conditions, we will have passed on through gain control 17 into frequency modulation-discriminator 9 (which may include an amplifier), an alternating current at 60 cycles which will be in phase with the original 60-cycle impulse 18 working up through the local oscillator, if the frequency of the first mixer-detector output 5 is below that of the local oscillator. Conversely it will be out of phase with the 60-cycle input 18, if the frequency of the first mixer-detector 5 is above the frequency of the local oscillator 6. The discriminator 9, in conventional fashion, serves to eliminate the radio-frequency currents in its input and to confine its output current to the same frequency as that of source 18, which in this example has been chosen as 60 cycles. The net result is that if we apply the same 60-cycle output 18 into one of the coil windings of the split phase motor 10 and use the output of the frequency modulation-discriminator 9 (which may include an amplifier), to energize the other coil winding of the split phase motor 10, we will have a resultant motion in one direction or the other, depending on whether the output of the first mixer-detector 5 is above or below the frequency of the swinging local oscillator 6. The motor 10 is of the well-known split-phase type, with the minor variation that the connections to the main and auxiliary windings, respectively, are not interconnected but the connections for these respective windings are brought out of the machine separately, thus making it possible so to connect the respective windings to their inputs as to provide the desired direction of rotation of the motor. The connections for one of these windings derive input from source 18, while the connections for the other winding derive input from frequency-modulation-discriminator 9. As described in any textbook on alternating-current machinery, (see, for example, pages 474 and 475 of "Electrical Circuits and Machinery, vol. II, Alternating Currents," by Hehre and Harness, 1942 addition, published by John Wiley & Sons, Inc.) the motor will then operate. The impedance of the auxiliary winding is such that the current in this winding has sufficient phase lag, with respect to the current in the main winding, to produce a rotating field in the motor. When the two input voltages are in phase, the motor will rotate in one direction. A reversal in phase of the input derived from discriminator 9 will cause the motor to rotate in the reverse direction. Of course, the motor will

not operate unless it obtains input from both source 18 and discriminator 9.

Mechanical connections 11 are taken from the split-phase motor 10 to the controlled oscillator 14, working on the adjustable condenser capacitor 12. Mechanical connections are tied in with the phase control such that if the frequency of the controlled oscillator is less than 200 kcs. below the selected harmonic 3, then a correction will be applied to capacitor 12 such as to decrease its capacity and thereby increase the frequency of the controlled oscillator set by capacitor 13.

Automatic volume control is introduced, as shown on 15, which works off capacity coupling 8 on the output of the second mixer detector 7, such that on rectification of the output of this capacity coupling 8, going into automatic volume control 15, a source of current will be obtained proportional to the intensity of the 60 cycle beat at this point. Automatic volume control 15 may, if desired, be coupled to the output of second mixer detector 7 independently of capacity coupling 8. If this 60 cycle beat is lower in intensity, the operation of the automatic volume control 15 will be such as to increase the gain at 17 to give more power to drive the split-phase motor.

It will also be arranged to decrease the gain control 16 so that less frequency swing will be accomplished on the local oscillator 6. The net result of these operations is such that as the output of the first mixer detector 5 approaches the setting of the local oscillator 6, we will get a lower output in the second mixer detector, which will be stepped up again through the gain control 17 and the discriminator 9 to keep driving the split-phase motor and at the same time the gain control 16 will decrease the frequency swing of oscillator 6 so that the net adjustment will come closer and closer to the desired frequency as this action continues to bring it near the required point.

The output of the controlled oscillator is taken to a transmitter which is not run at the same frequency, but either twice the frequency or one-half the frequency of the controlled oscillator 14 so that there will be less chance of interaction between the final output stages of the transmitter and the controlled oscillator stages.

It is obvious that this whole arrangement may be worked to control any point from 200 to 400 kc. on the local oscillator 6 as any other point from 200 to 400 may be taken such as 230 kc. as the reference note to compare with the difference between the frequencies of the controlled oscillator 14 and the selected harmonic 3. In this case, the controlled oscillator 14 will be locked to a point 230 kc. away from the selected harmonic.

Continuous control of crystal accuracy will thus be realized, at any selected point 200 to 400 kc. away from the selected harmonic, and the accuracy of the local oscillator 6 will only have to be arithmetically accurate to insure overall split-phase frequency control of the entire outfit.

The specification frequencies which are referred to in connection with the above description are merely illustrative and the system may be used with other frequencies of the crystal-controlled oscillator circuit, with a different range of possible frequency adjustment for the frequency-modulated oscillator circuit, and with a different frequency of the source of frequencies providing frequency-modulation.

Although two mixer detectors have been referred to above, it would of course, be possible to

combine the functions of both of these in a single tube, if desired.

I claim:

1. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move together, a source of relatively low frequencies, a second oscillator having a relatively constant output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, an electric circuit connection between said source and said motor, an electric circuit connection between all three oscillators and said motor, whereby said motor moves said adjustable part and thereby corrects the frequency of said controlled oscillator in accordance with whether or not the difference between the output frequency of said controlled oscillator and of said second oscillator is above or below that of said third oscillator.

2. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move together, a source of relatively low frequencies, a second oscillator having a relatively stable output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, a first mixer-detector in which the output frequencies of said controlled oscillator and of said second oscillator are combined to give an output equal to any difference between these frequencies, a second mixer-detector in which the output frequencies of said first mixer-detector and of said third oscillator are combined in such phase relation that the output of said second mixer-detector remains in phase with or is shifted 180° out of phase with the output of said source depending upon whether the frequency of said third oscillator is below or above that of said first mixer-detector, an electric circuit connection between said source and said motor, an electric circuit connection between said second mixer-detector and said motor whereby said motor moves said adjustable part in one direction or the other depending upon the phase relations of the outputs of said source and of said second mixer-detector fed to said motor and thereby corrects the frequency of said controlled oscillator.

3. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move

together, a source of relatively low frequencies, a second oscillator having a relatively stable output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, an electric circuit connection between said source and said motor, capacity coupling electrically connected in circuit to receive output from all three oscillators and arranged to modify the volume of its own output in proportion to the frequency of its input, an electric circuit connection between said capacity coupling and said motor, whereby said motor moves said adjustable part and thereby corrects the frequency of said controlled oscillator in accordance with whether or not the difference between the output frequency of said controlled oscillator and of said second oscillator is above or below that of said third oscillator.

4. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move together, a source of relatively low frequencies, a second oscillator having a relatively stable output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, an electric circuit connection between said source and said motor, frequency-modulation-discriminator means electrically connected in circuit to receive output from all three oscillators and arranged to pass and amplify current at the frequency of said source, and an electric circuit connection between said discriminator means and said motor, whereby said motor moves said adjustable part and thereby corrects the frequency of said controlled oscillator in accordance with whether or not the difference between the output frequency of said controlled oscillator and of said second oscillator is above or below that of said third oscillator.

5. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move together, a source of relatively low frequencies, a second oscillator having a relatively stable output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, an electric circuit connection between said source and said motor, capacity coupling electrically connected in circuit to receive output from all three oscillators and arranged to modify

the volume of its own output in proportion to the frequency of its input, automatic volume control means electrically connected to the output of said capacity coupling and modifying in proportion to the extent of any departure of the frequency of the controlled oscillator from its desired constant value, the extent of the frequency swing given by said source to said third oscillator, an electric circuit connection between said capacity coupling and said motor, whereby said motor moves said adjustable part and thereby corrects the frequency of said controlled oscillator in accordance with whether or not the difference between the output frequency of said controlled oscillator and of said second oscillator is above or below that of said third oscillator.

6. Means for maintaining constant the output frequency of an oscillator, said means comprising a controlled oscillator whose output frequency is to be maintained constant, an adjustable part of said oscillator whose adjustment varies the output frequency thereof, a split phase motor joined to said part so that said motor and said part move together, a source of relatively low frequencies, a second oscillator having a relatively stable output frequency which normally has a predetermined difference from the frequency of the controlled oscillator, a third oscillator including a movable part controlled by said source and whose movements cause frequency-modulation of said third oscillator and including also means for adjusting said third oscillator to have a mean frequency which is equal to the above predetermined difference, an electric circuit connection between said source and said motor, capacity coupling electrically connected in circuit to receive output from all three oscillators and arranged to modify the volume of its own output in proportion to the frequency of its input, automatic volume control means electrically connected to the output of said capacity coupling and modifying in inverse proportion to the intensity of that component of said output which has the modulation frequency, the volume of the power supplied said motor, and an electric circuit connection between said capacity coupling and said motor, whereby said motor moves said adjustable part and thereby corrects the frequency of said controlled oscillator in accordance with whether or not the difference between the output frequency of said controlled oscillator and of said second oscillator is above or below that of said third oscillator.

7. A frequency controller comprising: an oscillator which provides an output having great stability of frequency; a controlled oscillator whose output has a frequency which normally has a predetermined difference from the frequency of the output of the first-mentioned oscillator, such controlled oscillator containing an adjustable part by movement of which its output frequency is varied; a frequency-modulated oscillator capable of adjustment so that its output has a mean frequency which is equal to the above predetermined difference; means for frequency-modulating the frequency-modulated oscillator; a first mixer-detector in which the outputs of said first-mentioned oscillator and of said controlled oscillator are combined; a second mixer-detector in which the outputs of said first mixer-detector and of said frequency-modulated oscillator are combined in such phase relationship that the output of said second mixer-detector is in phase with the output of said frequency-modulating means when the output of the first mixer-detector is of higher frequency than that of the frequency-modulated

oscillator and is 180° out of phase with the output of said frequency-modulating means when the output of the first mixer-detector is of lower frequency than that of the frequency-modulated oscillator; a split-phase motor having coils, energized respectively by the output of said frequency-modulating means and by the output of said second mixer-detector; and a mechanical connection between said motor and said adjustable part, whereby said motor moves said adjustable part to bring the frequency of the output of said controlled oscillator to the desired value.

8. A frequency controller according to claim 7, having frequency-modulation-discriminator means connected between said second mixer-detector and one of the coils of said split-phase motor.

9. An electrical frequency control system comprising: a first oscillator circuit; a controlled oscillator circuit which includes tuning means and whose frequency normally has a predetermined difference from the frequency of the first circuit; a third oscillator circuit including means for adjusting this circuit so as to have a mean frequency which is equal to the above predetermined difference; means for frequency-modulating the third circuit; mixer-detector means which derive input from all three oscillator circuits; frequency-modulation-discriminator means which derive input from the mixer-detector means and which pass only current at substantially the modulation frequency of the third oscillator circuit; and control means which derive input from the frequency-modulation-discriminator means and from the frequency-modulating means and which are responsive to a variation of the controlled frequency from its normal value, to operate the tuning means in the controlled circuit to bring the controlled frequency to its normal value.

10. An electrical frequency control system comprising a first oscillator circuit, a controlled oscillator circuit which includes tuning means and whose frequency normally has a predetermined difference from the frequency of the first circuit, a third oscillator circuit including means for adjusting this circuit so as to have a mean frequency which is equal to the above predetermined difference, means for frequency-modulating the third circuit, a first mixer-detector deriving input from the first oscillator circuit and from the controlled oscillator circuit, a second mixer-detector deriving input from the first mixer-detector and from the third oscillator circuit, frequency-modulation-discriminator means deriving input from the second mixer-detector and passing only current at substantially the modulation frequency of the third oscillator circuit, and control means deriving input from the frequency-modulation-discriminator means and from the frequency-modulating means and responsive to a variation of the controlled frequency from its normal value, to operate the tuning means in the controlled circuit to bring the controlled frequency to its normal value.

11. An electrical frequency control system, as described in claim 10, which includes automatic volume control means deriving input from the second mixer-detector for modifying in inverse proportion to the volume of that component of the input which has the modulation frequency, the volume of that part of the input to the control means which is derived from the frequency-modulation-discriminator means.

12. An electrical frequency control system, as described in claim 10, which includes automatic volume control means deriving input from the second mixer-detector for modifying the extent of the frequency swing of the third oscillator circuit in proportion to the difference of the controlled frequency from its normal value.

13. An electrical frequency control system, as described in claim 10, which includes automatic volume control means deriving input from the second mixer-detector for modifying in inverse proportion to the volume of that component of the input which has the modulation frequency, the volume of that part of the input to the control means which is derived from the frequency-modulation-discriminator means, such automatic volume control means also modifying the extent of the frequency swing of the third oscillator circuit in proportion to the difference of the controlled frequency from its normal value.

14. An electrical frequency control system, as described in claim 10, which includes coupling means inserted between the second mixer-detector and the frequency-modulation-discriminator means for modifying the volume of the input to the latter means in proportion to the frequency of the output of the second mixer-detector.

15. An electrical frequency control system, as described in claim 10, which includes coupling means inserted between the second mixer-detector and the frequency-modulation-discriminator means for modifying the volume of the input to the latter means in proportion to the frequency of the output of the second mixer-detector, and also includes automatic volume control means deriving input from the coupling means for modifying in inverse proportion to the volume of that component of the input which has the modulation frequency, the volume of that part of the input to the control means which is derived from the frequency-modulation-discriminator means.

16. An electrical frequency control system, as

described in claim 10, which includes coupling means inserted between the second mixer-detector and the frequency-modulation-discriminator means for modifying the volume of the input to the latter means in proportion to the frequency of the output of the second mixer-detector, and also includes automatic volume control means deriving input from the coupling means for modifying the extent of the frequency swing of the third oscillator circuit in proportion to the difference of the controlled frequency from its normal value.

17. An electrical frequency control system as described in claim 10, which includes coupling means inserted between the second mixer-detector and the frequency-modulation-discriminator means for modifying the volume of the input to the latter means in proportion to the frequency of the output of the second mixer-detector, and also includes automatic volume control means deriving input from the coupling means for modifying in inverse proportion to the volume of that component of the input which has the modulation frequency, the volume of that part of the input to the control means which is derived from the frequency-modulation-discriminator means, such automatic volume control means also modifying the extent of the frequency swing of the third oscillator circuit in proportion to the difference of the controlled frequency from its normal value.
